[57] CLAIM

The ornamental design for a recessed lighting fixture trim having a decorative portion with a translucent band, as shown and described.

DESCRIPTION

FIG. 1 is a lower front perspective view of a recessed lighting fixture trim having a decorative portion with a translucent band, the ceiling being shown in broken lines for illustrative purposes only and forming no part of the claimed design;

FIG. 2 is a cross-sectional view thereof, the recessed lighting fixture and ceiling being shown in broken lines for illustrative purposes only and forming no part of the claimed design;

FIG. 3 is a front elevational view thereof, which view is identical to rear right and left elevational views;

FIG. 4 is a top plan view thereof; and,

FIG. 5 is a bottom plan view thereof.

Recessed lighting fixture trim having a decorative portion with a translucent band is shaded to show that the band is translucent.
